UNITED STATES PATENT OFFICE

EMANUEL DYM, OF PITTSBURGH, PENNSYLVANIA, ASSIGNOR TO PORCELIER MANUFACTURING COMPANY, OF GREENSBURG, PENNSYLVANIA, A CORPORATION OF PENNSYLVANIA

DESIGN FOR A CONTAINER FOR COOLING AND DISPENSING WATER OR BEVERAGES

Application filed June 27, 1932. Serial No. 44,200. Term of patent 7 years.

To all whom it may concern:

Be it known that I, EMANUEL DYM, a citizen of the United States, residing at Pittsburgh, in the county of Allegheny and State of Pennsylvania, have invented a new, original, and ornamental Design for a Container for Cooling and Dispensing Water or Beverages, of which the following is a specification, reference being had to the accompanying drawing, forming a part hereof.

Figure 1 is a perspective view of a container embodying my design;

Figure 2 is a top plan view thereof;

Figure 3 is an end view of that end opposite the spout; and

Figure 4 is a transverse section substantially in the plane of line IV—IV of Figure 2.

I claim:

The ornamental design for a container for cooling and dispensing water or beverages, as shown.

In testimony whereof I have hereunto subscribed my name this 25th day of June, 1932.

EMANUEL DYM.
